UNITED STATES PATENT OFFICE.

LOUIE JANIK, OF HAVELOCK, NEBRASKA, ASSIGNEE OF ONE-HALF TO CHARLES W. JONAS, OF HAVELOCK, NEBRASKA.

MOTOR.

940,801.

Specification of Letters Patent. Patented Feb. 28, 1910.

Application filed October 17, 1908. Serial No. 453,807.

To all whom it may concern:

Be it known that I, Louis JANIK, a citizen of the United States, residing at Have-
lock, in the county of Lancaster and State
of Nebraska, have invented certain new and
useful Improvements in Motors, of which
the following is a specification.

My invention relates to reciprocating mo-
tors propelled by compressed air, steam or
similar motive power and has for its object
the provision of an improved construction of
motor that is provided with a valve for con-
trolling the exit and exhaust of the motive
element to and from the motor cylinder that
is operated by the motive element to change
the direction thereof to the motor, the opera-
tion of the valve being automatically con-
trolled by the piston in the motor cylinder.

I have described the construction and op-
eration of my improved motor at length
hereinafter and illustrated it in the accom-
panying drawings in which—

Figure 1 is a longitudinal sectional view
of my improved motor. Fig. 2, a top plan
view on a smaller scale, Fig. 3, a cross-section
view on the line $a-a$ of Fig. 1, Fig. 4, a
similar view on the line $y-y$ of Fig. 1, and
Fig. 5, a similar view on the line $z-z$ of
Fig. 1.

In the drawings similar reference char-
acters indicate corresponding parts in all
of the views.

My improved motor comprises the cylin-
der 13, the valve housing 14 secured at one
end of said cylinder and the cylinder head
15 at its other end.

16 indicates the motor piston in cylinder
13 having its rod 17 extended through a hole
18 in cylinder head 15.

19 indicates the valve piston in cylinder
13 above the joint between
said housing and cylinder 13 on which is
seated valve casing 20 held in position by
plug 21. Plug 21 is formed with a chamber
22 and a port 23 communicating therewith
for the admission of compressed air, steam
or other preferred motive agent. Shoulder
19 also forms a chamber 19^a between valve
casing 20 and cylinder 13.

24 indicates the valve chamber in casing
20 in which is slidably mounted the piston
25 formed with two annular grooves 26 and
26^a. The ends of chamber 24 are formed
with protuberances 24^a that form spaces 27

and 28 at the ends of the chamber to admit 85
the air or steam to propel said piston to
one end or the other of the chamber as will
be hereinafter described.

29 and 30 indicate ports connecting cham-
bers 22 and 24, 31 and 32 other ports con-
necting chambers 19^a and 24, ports 29 and
31 being aligned so that when the piston 25
is in such a position that groove 26 is aligned
with said ports the air, steam or other mo-
tive force passes therethrough from chamber 85
22 to chamber 19^a and the piston 12 is driven
downwardly.

33 indicates ports in the side of chamber
24 connecting with pipe 34, which empties
into the lower end of cylinder 13, so that 70
when piston 25 is in such a position that
groove 26 is aligned with ports 30 and 33 the
motive agent passes through said ports and
pipe 34 to the lower end of the cylinder 13
and the piston 16 is driven upwardly. 75

35 indicates the exhaust duct, 36 exhaust
ports connecting chamber 24 and duct 35
and in alignment with port 32 so that when
the piston 25 is in the position described in
the preceding paragraph and the motive 80
agent is entering the lower end of cylinder
13 to drive the piston 16 upwardly the
groove 26 is aligned with ports 32 and 36
and the air, steam or other agent in the
upper end of the cylinder is exhausted into 85
duct 35. 37 indicates other ports connecting
chamber 24 and exhaust duct 35, and 38
ports connecting chamber 24 and pipe 31,
the mouths of said ports 37 and 38 where
they empty into chamber 24 being in align-
ment so that when the valve piston 25 is in 90
the position first described, and the air,
steam or other agent is entering the upper
end of cylinder 13 to drive the piston 12
downwardly the lower end of the cylinder 95
is exhausting through pipe 31, and ports 38
and 37 into duct 35.

In order that the valve piston may be au-
tomatically actuated, so that the air, steam,
etc., is admitted to and exhausted from the 100
two ends of cylinder 13 as above described,
I provide a pipe 39 connecting chamber 27
and cylinder 13 above the line marking the
extremity of the downward movement of
piston 16, and a pipe 40 connecting chamber 105
28 and cylinder 13 below the line marking
the extremity of the upward movement of
said piston.

41 and 42 indicate exhaust ports connecting chambers 27 and 28 respectively with duct 35.

The operation of the motor will be understood to be as follows: Assuming that valve piston 25 is in such a position that groove 26 therein is in alignment with ports 29 and 31, as shown in Fig. 1, the air, steam, etc., entering chamber 22 through port 28 will 10 pass through said aligned ports 29 and 31 and groove 26 into chamber 19 at the upper end of cylinder 13 and the motor piston 12 will be forced downwardly. As soon as the piston 16 uncovers the entrance to pipe 39 15 the air or steam will flow through said pipe 39 to chamber 27 and force valve piston 25 over so that groove 26 is aligned with ports 30 and 33 and the air or steam will flow therethrough from chamber 22 to pipe 34 20 and into the lower end of the cylinder forcing the piston 16 upwardly. At this time the groove 26 is in alignment with ports 32 and 36 and the upper end of cylinder 13 exhausts therethrough into duct 35, chamber 25 27 also exhausting through port 41 into said duct 35. Before the piston 16 reaches the upper extremity of its stroke the entrance to pipe 40 is uncovered and the air or steam 30 will flow therethrough into chamber 28 and force the valve 25 back to its first described position to actuate the piston 16 downwardly. When the piston 16 is being forced

downwardly the lower end of cylinder 13 is exhausting through pipe 34, and ports 37 and 38 and groove 26 said ports and groove 35 being aligned when the valve piston is in this position. At the same time chamber 28 is exhausting through port 42 into duct 35.

Having thus described my invention what I claim is—

In a motor, a cylinder, a reciprocating piston mounted in said cylinder, a casing at one end of the cylinder having a transverse cylindrical bore therein, an imperforate cylindrical valve mounted in said bore and having annular grooves therein, said casing having an inlet duct and ports connecting said duct and bore, ducts in alignment with the inlet ports leading to the two ends of the cylinder, exhaust ports in said casing and communicating with said bore, exhaust ducts in alignment with said exhaust ports and communicating with the two ends of the cylinder, and means controlled by the piston to move the cylindrical valve so that the grooves therein are alternately in alignment with the exhaust and inlet ports aforesaid.

In testimony whereof I hereto affix my signature in the presence of two witnesses:

LOUIS JANIK
